DESIGN FOR A PORTABLE SAMPLE CARRIER

Harry L. Hoenigsberger, Chicago, Ill.

Application July 22, 1939, Serial No. 86,184

Term of patent 3½ years

To all whom it may concern:

Be it known that I, Harry L. Hoenigsberger, a citizen of the United States, residing at Chicago, in the county of Cook and State of Illinois, have invented a new, original, and ornamental Design for a Portable Sample Carrier, of which the following is a specification, reference being had to the accompanying drawing, forming part thereof wherein—

Figure 1 is a perspective view of a portable sample carrier showing my new design; and
Fig. 2 is a front elevation thereof.

I claim:

The ornamental design for a portable sample carrier, as shown.

HARRY L. HOENIGSBERGER.
